MUSICAL INSTRUMENT

Allen Loomis, Elkhart, Ind., assignor to C. G. Conn, Ltd., Elkhart, Ind., a corporation of Indiana

Application August 15, 1936, Serial No. 96,142

13 Claims. (Cl. 84—386)

This invention relates to the tuning of musical instruments, and is illustrated as embodied in clarinets or the like having improved tuning means.

5 An object of the invention is to provide a simple and accurate means for tuning such an instrument by shifting axially relatively to each other telescoping sections of the instrument, thereby changing the effective length of the air 10 column, the tuning means preferably being arranged to limit the separation of the sections in the normal tuning operation to prevent unintentional disengagement of the operating mechanism.

15 The telescoping sections of the instrument are shown provided with means, such as oppositely-directed (i. e. right and left) external threads, engaged by operating means (such as corresponding internal threads) carried by a tuning collar 20 or sleeve which surrounds and substantially conceals the telescoping portions of the relatively-shiftable sections. One feature of the invention relates to facilitating the assembly of the parts by making the thread on one section of smaller 25 diameter than that on the other section, the internal threads on the collar being of corresponding different diameters.

An important feature of the invention relates 30 to the provision of means, preferably normally concealed by the collar, for limiting the separating movement of the telescoping sections to prevent unintended disengagement of their threads from the operating threads of the tuning collar or sleeve. At least in one position of the collar, however, the separation-limiting means should 35 be accessible so that it can be rendered inoperative when the instrument is being taken apart.

I prefer to mount a radially projecting part 40 removably on one of the telescoping sections within a slot on the other section, and the collar may then be formed with an opening which aligns with, and permits the removal of, the projection in one position of the collar. In the arrangements illustrated, one of the telescoping sections 45 has a keyway interrupting its external thread and receiving a guide key or the like carried by the other section, the key having the slot embracing the removable radial projection to limit separation of the sections.

Another feature of the invention relates to shortening the tuning mechanism by arranging the mouthpiece receiver with a tongue or key, arranged to seat in a keyway as described above, 55 spaced radially outside the inside slide, so that

the outside slide of the body tenon receiver fits between the tongue and the inside slide.

The above and other objects and features of the invention, including various novel combinations of parts and desirable particular constructions, will be apparent from the following description of the illustrative embodiments shown in the accompanying drawing, in which:

Figure 1 is a side elevation of the upper or mouthpiece end of a wood clarinet provided with one form of my improved tuning means;

Figure 2 is a bottom plan view, looking in the direction of the arrows 2—2 in Figure 1, but with the tuning collar or sleeve broken away in central section to show the parts inclosed therein;

Figure 3 is a partial section on the line 3—3 of Figure 2;

Figure 4 is a detail of part of Figure 3 on a much larger scale;

Figure 5 is a partial side elevation of a metal 20 clarinet provided with a somewhat different embodiment of my invention;

Figure 6 is a plan view thereof, looking in the direction of the arrows 6—6 in Figure 5, and with the tuning collar broken away in central 25 section;

Figure 7 is a partial section on the line 7—7 of Figure 6; and

Figure 8 is an elevation, partly broken away in central section, showing a third embodiment.

The clarinet illustrated in Figures 1—3 includes an instrument body 10, and a mouthpiece 12 intended for use with a reed (not shown), connected by novel tuning means for shifting these parts relative to each other axially (i. e. lengthwise) of the instrument to change the effective length of the air column.

In the arrangement illustrated, the tuning means comprises telescoping sections 14 and 16, formed at their ends with sockets or tenon receivers into which fit respectively the usual corked tenons on the ends of the instrument body 10 and the mouthpiece 12, as shown in Figure 3. It will be noted that the lefthand end of section 16 is very thin, and telescopes inside of the section 14, so that there is a substantially continuous and uniform-diameter wall inclosing the air column, in all positions of the tuning mechanism. These sections may, if desired, be built up by soldering thin-walled tubing to rings of heavier material.

The end of the section 14 is formed with an external thread 18, interrupted at one point to provide an undercut keyway extending in the direction of the length of the instrument and slid-

ably receiving a guide key 20 carried by and projecting from a sleeve 22 pressed permanently onto (and if desired soldered or otherwise secured to) the section 16 against the shoulder which forms the base of the socket receiving the end of the mouthpiece 12. The sleeve 22 is formed with external threads 23 of somewhat greater diameter than the threads 18. The section 16 thus in effect carries, spaced radially outward therefrom, the key 20, and the section 14 is fitted or nested between these two parts. This makes for great compactness, shortening the entire tuning mechanism materially as compared to earlier designs having the same range of adjustment.

The threads 18 and the threads 23 on the sleeve 22 are directed in opposite directions, one being a righthand thread and the other being a lefthand thread, and they are engaged by corresponding right-and-left internal threads 25 of two corresponding different diameters formed on a part 24 permanently secured in the interior of a tuning collar or sleeve 26 which normally incloses and protects the telescoping portions of the sections 14 and 16 throughout their entire lengths. The difference in the diameters facilitates assembling the parts.

As previously explained, the guide key 20 is formed with a slot 28 extending in the direction of the length of the instrument, and which embraces a removable radially-projecting part such as a pin 30 having its base threaded into the section 14 centrally of the keyway which interrupts the threads 18. This, it will be seen, limits separation of the sections 14 and 16 and prevents unintentional disengagement of their threads from the operating threads 25 on part 24.

The collar 26 is formed with a radial opening therethrough, normally closed by a removable setscrew or the like 32 if desired, which in one position alines with the stop pin 30 and through which the stop pin can be removed when the instrument is being taken apart. The ends of collar 26 may be protected by suitable ferrules 34.

The arrangement illustrated in Figures 5-7 is substantially as described above, except that it is designed for use with a metal clarinet or similar instrument. Parts corresponding to parts in Figures 1-4 are indicated by the same reference characters increased by 100. The principal difference is in the size of the parts; however, the thread-carrying sleeve 122 is illustrated as integral with the section 116, and a separate thin tube 117 soldered thereto forms the portion telescoping into the section 114. In this arrangement, the pin 130 becomes accessible (for removal) beyond the edge of the collar 126, when collar 126 is turned to bring the pin 130 into the extreme lefthand end of the slot 128.

Figure 8 illustrates an arrangement which is the same as that in Figures 1-3 except that a protecting sleeve 234, surrounding the end of the collar 26, is integral with a telescoping section 214 which may otherwise be of the same construction as the section 14. In this arrangement, turning the collar 26 makes the adjustment in the same manner as in the embodiment of Figures 1-4, but the end of the collar is covered by the sleeve 234.

It will be noted that the above-described construction provides a relatively long and easily manipulated tuning collar or sleeve, that in all of the joints the inside part points toward the lower end of the instrument so that moisture

cannot work into the joints, that the means for keying the sections together does not interrupt the internal surface of the instrument as in some prior constructions, that a wide range of adjustment is provided with a very short tuning mechanism, that permanent attachment of intricate parts to the instrument body is avoided, that there is no substantial interference with the resonance of the instrument by loose or doubled parts or the like, and that the tuning mechanism is easily and accurately operated and is not expensive to manufacture.

While several illustrative constructions have been described in detail, it is not my intention to limit the scope of the invention to those particular constructions, or otherwise than by the terms of the appended claims.

I claim:

1. A tuning device for wind reed musical instruments comprising telescoping sections having respectively right and left external threads and provided with interengaging parts preventing relative turning, a collar surrounding the telescoping portions of said sections and which is provided with internal right and left threads interengaging respectively with said external threads, said collar being operable to shift said sections relatively to each other axially to tune the instrument, and means within said collar for normally limiting separation of said sections to prevent disengagement of the internal and external threads.

2. A tuning device for wind reed musical instruments comprising telescoping sections provided with interengaging parts preventing relative turning and with means limiting separation of said sections, and a collar surrounding the telescoping portions of said sections, said collar and said sections having interengaging means by the operation of which said collar shifts said sections relatively to each other axially to tune the instrument, said separation limiting means normally limiting separation of said sections to prevent disengagement of the interengaging means on the collar and said sections.

3. A tuning device for wind reed musical instruments comprising telescoping sections having respectively right and left external threads and provided with interengaging parts preventing relative turning, a collar surrounding the telescoping portions of said sections and which is provided with internal right and left threads interengaging respectively with said external threads, said collar being operable to shift said sections relatively to each other axially to tune the instrument, and means carried by said sections for normally limiting separation of said sections to prevent disengagement of the internal and external threads.

4. A tuning device for wind reed musical instruments comprising telescoping sections provided with interengaging parts preventing relative turning and with means limiting separation of said sections, and a collar surrounding the telescoping portions of said sections, said collar and said sections having interengaging means by the operation of which said collar shifts said sections relatively to each other axially to tune the instrument, said separation limiting means normally limiting separation of said sections to prevent disengagement of the interengaging means on the collar and said sections, said separation-limiting means being accessible in one position of the collar and being constructed and arranged readily to be rendered inoperative when the collar is in

said position, to facilitate taking the instrument apart when desired.

5. A wind reed musical instrument comprising telescoping sections one of which is keyed to the other to prevent relative turning by a guide key seated in a keyway in the other, said key being formed with a slot extending lengthwise of the instrument and said other section being removably provided with a radially projecting part extending into said slot to limit the separation of said sections, a collar surrounding the telescoping portions of said sections and which has means which in one position of the collar affords access to said projecting part to permit its removal when the instrument is being taken apart, and interengaging means carried by said collar and said sections constructed and arranged to be operated by turning the collar to shift said sections axially relative to each other to tune the instrument.

20 6. A wind reed musical instrument comprising telescoping sections one of which is keyed to the other to prevent relative turning by a guide key seated in a keyway in the other, said key being formed with a slot extending lengthwise of the instrument and said other section being removably provided with a radially projecting part extending into said slot to limit the separation of said sections, a collar surrounding the telescoping portions of said sections and which is formed with an opening therethrough which in one position of the collar can be aligned with said projecting part to permit its removal when the instrument is being taken apart, and interengaging means carried by said collar and said sections constructed and arranged to be operated by turning the collar to shift said sections axially relative to each other to tune the instrument, said interengaging means including oppositely directed threads on the exterior of said sections and one of which is intersected by said keyway and corresponding oppositely directed threads on the interior of said collar and interengaging with the threads on said sections.

7. A wind reed musical instrument comprising telescoping sections externally provided with oppositely-directed threads one of which is interrupted by a keyway in the direction of the length of the instrument and the other of which has a guide key seated in said keyway, one of said threads being of greater diameter than the other, and a collar surrounding the telescoping portions of said sections and having internal oppositely-directed threads of different diameters interengaging with the threads on said sections respectively.

8. A tuning device for wind reed musical instruments comprising telescoping sections provided with interengaging parts preventing relative turning and with means limiting separation of said sections, and a collar surrounding the telescoping portions of said sections, said collar and said sections having interengaging means by the operation of which said collar shifts said sections relatively to each other axially to tune the instrument, said separation limiting means normally limiting separation of said sections to prevent disengagement of the interengaging means on the collar and said sections, said collar being of a length to inclose substantially the entire lengths of said telescoping sections.

9. A wind reed musical instrument comprising telescoping sections externally provided with oppositely-directed threads one of which is interrupted by a keyway in the direction of the length of the instrument and the other of which has a guide key seated in said keyway, one of said threads being of greater diameter than the other, and a collar surrounding the telescoping portions of said sections and having internal oppositely-directed threads of different diameters interengaging with the threads on said sections respectively, said collar being of a length to inclose substantially the entire lengths of said telescoping sections.

10. A wind reed musical instrument comprising telescoping sections which are adjustable lengthwise of the instrument to tune the instrument, and the inner one of which is provided at one end with a key projecting outside of the outer section parallel to the longitudinal axis of the instrument, said outer section being provided with a keyway into which said key slidably fits, whereby said outer section is nested between the inner section and the key.

11. A wind reed musical instrument comprising telescoping sections which are adjustable lengthwise of the instrument to tune the instrument, and the inner one of which is provided at one end with a key projecting outside of the outer section, said outer section being provided with a keyway into which said key slidably fits, whereby said outer section is nested between the inner section and the key, in combination with a collar encircling said telescoping sections and said key, and means within and operated by said collar for shifting said sections axially upon each other to tune the instrument.

12. A wind reed musical instrument comprising telescoping sections which are adjustable lengthwise of the instrument to tune the instrument, and the inner one of which is provided at one end with a key projecting outside of the outer section, said outer section being provided with a keyway into which said key slidably fits, whereby said outer section is nested between the inner section and the key, in combination with a collar encircling said telescoping sections and said key, and which has threads arranged internally thereof, and parts on said sections formed with external threads meshing with the internal threads of said collar for shifting said sections axially upon each other to tune the instrument.

13. A wind reed musical instrument comprising telescoping sections which are adjustable lengthwise of the instrument to tune the instrument, and the inner one of which is provided at one end with a key projecting outside of the outer section, said outer section being provided with a keyway into which said key slidably fits, whereby said outer section is nested between the inner section and the key, in combination with a collar encircling said telescoping sections and said key, and which has threads arranged internally thereof, and parts on said sections formed with external threads meshing with the internal threads of said collar for shifting said sections axially upon each other to tune the instrument, said keyway being arranged to form an interruption of the threads on the outer one of said sections.
